UNITED STATES PATENT OFFICE.

EDWARD C. WENTE, OF NEW YORK, N. Y., ASSIGNOR TO WESTERN ELECTRIC COMPANY,
INCORPORATED, OF NEW YORK, N. Y., A CORPORATION OF NEW YORK.

PIEZO-ELECTRICAL VOLTAGE INDICATOR.

Application filed November 13, 1920. Serial No. 423,845.

To all whom it may concern:

Be it known that I, EDWARD C. WENTE, a citizen of the United States, residing at New York, in the county of New York, 5 State of New York, have invented certain new and useful Improvements in Piezo-Electrical Voltage Indicators, of which the following is a full, clear, concise, and exact description.

10 This invention relates in general to electric current detecting devices and particularly to such devices for use in connection with the recording of variations in voltage intensity.

15 In apparatus heretofore available for the analysis of complex sound waves, the analysis of vowel sounds has been quite successfully accomplished. For the analysis of consonant sounds however, it is essential 20 that the apparatus have little or no distortion for frequencies up to about 10,000 cycles per second. Considerable difficulty has heretofore been experienced in designing an oscillograph which has a uniform 25 characteristic and is free from transient oscillations over this wide range of frequencies.

The principal object of the present invention is to provide an instrument simple, 30 accurate, positive in action, for recording wave forms of alternating currents without distortion over a wide range of frequencies.

A further object of the invention is to provide a device with which may be used 35 a larger reflector than is ordinarily possible, so that when the device is used as an oscillograph vibrator or similar apparatus the intensity of the focusing light will be greatly increased.

40 It has been found that in an ordinary oscillograph of the oil damped type, due to the change in the viscosity of the oil, the frequency characteristic is altered with changes in temperature. It is a further object of this invention to provide a device 45 for indicating the intensity of an electric current which will be unaffected by changes in atmospheric conditions.

It has been found that piezo-electric crystals, such as quartz are admirably adapted 50 for constructing vibrators having great stiffness. From a consideration of the following detailed description of the invention in its preferred form, taken in connection 55 with the accompanying drawings and ap-

pended claims, further objects and features of the invention will be apparent.

Fig. 1 shows in perspective the invention as applied to an oscillograph system; and Fig. 2 is a longitudinal cross-sectional view 60 showing the electrical connections with the actuating elements.

Referring first to Fig. 1; 3 and 4 are two thin piezo-electric crystal blades, such as quartz, of the same shape and size, rigidly 65 fastened at one end in a moderately massive block 5; to the other end is attached an oscillograph mirror 6 of proper curvature. The supporting block 5 must be of considerably greater mass than the mirror 6, in order 70 to insure against vibrations in the block instead of in the mirror. The quartz blades should be cut from the natural crystal in such a way that the greatest change in length is produced when a potential is applied between the electrodes placed on their lateral faces. The method of cutting will 75 of course vary with the type of piezo-electric crystal employed. Quartz, tourmaline and Rochelle salts, for example, are all 80 piezo-electrically active, but the method of cutting from the natural crystal may differ in each case. The electrodes should be so connected into the circuit that as one blade elongates, the other contracts; the mirror 6 85 will then be rotated about its center of gravity. To prevent buckling, the quartz blades are held between metal slabs 7, which however, are not clamped against the quartz 90 so tightly as to interfere with their longitudinal movement.

In the sectional view shown in Fig. 2, piezo-electrical blades 3 and 4 are securely held at one end in the block 5. The electrodes 9 and 10 of metal foil are placed on 95 the lateral faces of the quartz blades. The metallic electrodes may, if desired, be electrolytically deposited upon the blades. The electrodes 9 and 10 are connected into the circuit by means of electrical connections 100 at 8.

The air gaps between the electrodes 9 and 10 and the metal plates 7 are exceedingly small so that any lateral vibrations of the blades 3 and 4 are damped by the film of 105 air. This film of air acts as a cushion and will give sufficient damping to minimize lateral motion.

One method for the analysis of complex sound waves is described by Rankine (Proc. 110

London Phys. sec. 31,242 (1919) and 32, 78 (1919). The following is a description of the actual working of the present invention as applied to the Rankine system for varying the intensity of the light falling on a photographic plate in accordance with a periodic stimulus: The light from the source 11 is brought to focus on the oscillograph mirror 6 by means of the lens 12. After reflection, it is again brought to focus on the photographic plate at 13 by means of the lens 14. On the plane surface 15 of the lens 12 is placed a grid consisting of opaque strips which are parallel to each other and spaced so that the distances between the adjacent strips are the same and equal to the width of the strips. On the plane surface 16 of the lens 14, an exactly similar grid is placed. If the mirror 6 has the proper curvature and if the distances between the lenses and the mirror are equal, an image of the grid at 15 of exactly the same size as the grid itself will be formed on the plane surface 16. The image of the grid at 15 may then be superimposed on the grid at 16. If the mirror 6 is in a position such that the image of the strips at 15 falls exactly on clear spaces of the grid at 16, no light will be transmitted to the point 13, whereas a maximum amount of light will be transmitted when the image of the strips at 15 lies exactly on the strips of the grid at 16. If the equilibrium point of the angular position at mirror 6 is properly adjusted, the light transmitted by the system will be a linear function of the angular displacement of the mirror about its equilibrium point. A photographic record may then be obtained of the motion of the mirror 6, by moving the plate past the point 13.

With a piezo-electric vibrator such as is described in the present invention, a much larger mirror than can ordinarily be used in an oscillograph vibrator may be used, so that the intensity of the light reaching the film may be greatly increased. This light may be focused directly on the photographic plate. By means of this type of vibrator it is possible to record the wave form of high frequency electric currents without distortion.

If an oscillograph of this type is used with a condenser-transmitter and a distortionless amplifier, a system can be so designed that there is practically no distortion over a wide range of frequencies. It will thus be possible to obtain accurate

records of consonant sounds. Because of the importance of consonant sounds in speech transmission, this method will yield results of a greater value than have heretofore been obtainable. 60

While the invention has been herein described in its preferred form, it is not intended to limit to the specific structure disclosed except within the scope of the appended claims. 65

What is claimed is:

1. In a device for indicating the intensity of an electric current, a plurality of piezo-electric crystalline blades rigidly supported 70 at one end, a reflector supported by the free ends of said blades, and means for laterally supporting said blades.

2. In a device for indicating the intensity of an electric current, a plurality of piezo-electric crystalline blades rigidly supported 75 at one end, a reflector attached to the other end, and air damping means for minimizing lateral motion of said blades.

3. In a device for indicating the intensity 80 of an electric current, a supporting member, a plurality of piezo-electric crystalline blades supported at one end in said member, a member mechanically movable by said blades, and means for damping the lateral 85 movement of said blades to prevent them from buckling when distorted.

4. In a device for indicating the intensity of an electric current, a supporting member, a plurality of piezo-electric crystalline 90 blades supported at one end in said member, a member mechanically movable by said blades, and means for damping the lateral movement of said blades comprising supporting members on the lateral faces 95 thereof, but separated therefrom by an air gap.

5. In a device for indicating the intensity of an electric current, a supporting member, a plurality of piezo-electric crystalline 100 blades supported at one end in said member, electrodes disposed on the lateral faces of said blades, supporting members adjacent the lateral faces of said blades, but separated therefrom by air gaps, a reflector 105 mounted on the free end of said blades, and means for connecting said electrodes in an electric circuit.

In witness whereof, I hereunto subscribe my name this 12th day of November, A. D., 110 1920.

EDWARD C. WENTZ.
